(57) **CLAIM**

The ornamental design for “flatware,” as shown and described.

DESCRIPTION

FIG. 1 is a top, front perspective view of flatware in accordance with a first example embodiment of my new design; FIG. 2 is a top, rear perspective view the example embodiment of FIG. 1;

FIG. 3 is a front view of the embodiment of FIG. 1;
FIG. 4 is a top plan view of the embodiment of FIG. 1;
FIG. 5 is a bottom view of the embodiment of FIG. 1;
FIG. 6 is a right side view of the embodiment of FIG. 1;
FIG. 7 is left side view of the embodiment of FIG. 1;
FIG. 8 is a top, front perspective view of flatware in accordance with a second example embodiment of my new design;
FIG. 9 is a bottom, rear perspective view the example embodiment of FIG. 8;
FIG. 10 is a front view of the embodiment of FIG. 8;
FIG. 11 is a top plan view of the embodiment of FIG. 8;
FIG. 12 is a bottom view of the embodiment of FIG. 8;
FIG. 13 is a right side view of the embodiment of FIG. 8; and,
FIG. 14 is left side view of the embodiment of FIG. 8.
